UNITED STATES PATENT OFFICE

2,450,893

HIGH-FREQUENCY TUBE STRUCTURE

William W. Hansen and John R. Woodyard, Gar-
den City, N. Y., assignors to The Sperry Cor-
poration, a corporation of Delaware

Original application May 17, 1941, Serial No.
393,868. Divided and this application Novem-
ber 28, 1941, Serial No. 420,771

20 Claims. (Cl. 250—27.5)

1

This invention relates, generally, to high frequency tube structures, having enclosed oscillating circuits, and their associated apparatus, of the general type disclosed in Letters Patent No. 2,242,275, and has reference, more particularly, to novel improvements in this type of structure and apparatus operating at ultra high frequencies, of the order of 10^9 cycles per second. The present application is a division of our co-pending application Serial No. 393,868 for High-frequency tube structures, filed May 17, 1941, and now U. S. Patent No. 2,406,372, granted August 27, 1946.

One object of the present invention is to provide a novel tube structure incorporating a novel and efficient buffer stage or resonator forming an integral part of and contained in the same envelope with an electron discharge tube of the type disclosed in the above patent, and which may serve as an oscillator, modulator, etc., thereby permitting operation of the tube at higher power limits without decreasing its frequency stability.

A still further object is to provide novel ultra-high frequency apparatus having two aligned cavity resonators adapted to pass therethrough a grouped electron stream, the resonators being separated by a relatively small space permitting the grouped property of the beam to be maintained, while preventing the extraction of energy from one of the resonators from affecting the operation of the other resonator.

Another object is to provide novel means in an electron discharge device for increasing the capacitance of the electron-permeable regions of a resonator.

Another object of the present invention is to provide a novel tuning structure for ultra-high frequency tubes of the above-mentioned type including a micrometer type fine adjustment incorporating a flexible cantilever arrangement for obtaining greater exactness of tuning adjustment than heretofore possible.

A further object is to provide a novel form of cavity resonator or resonating chamber which is very compact for a given operating frequency.

Another object is to provide a novel electron collector electrode for ultra-high frequency apparatus having an electron-permeable resonator, the collector electrode being located externally of the resonator.

Other objects and advantages will become apparent from the specification taken in connection with the accompanying drawings, wherein,

Fig. 1 is a view in side elevation and partly

in section of the electron discharge tube structure;

Fig. 2 is a perspective view of the fine tuning adjustment of the tube of Fig. 1;

Fig. 3 is a side elevation view of the device of Fig. 1 operated as an oscillator-buffer.

In the drawings, Fig. 1 shows an electron discharge tube structure 1 comprising an indirectly heated cathode 2 having a heater 3, a modulating grid 5 and spaced, cylindrical, resonators or resonating chambers 7, 9, 11. These resonators have rigid dished walls 13, 15, 17 and opposed flexible walls 19, 21, 23, respectively, the dished walls being centrally apertured and provided with grids. 15 Flexible walls 19 and 21 of resonators 7 and 9 are joined by a drift tube 25 also having grids at its ends opposite the grids of walls 13 and 15. Dished flanges 16 and 16' are provided on opposite ends of tube 25 adjacent and substantially 20 parallel to resonator walls 13 and 15 respectively. A similar flange 16'' is provided on the end of tube 11 adjacent wall 17. Flanges 16, 16' and 16'' thereby provide coextensive adjacent conductive surfaces of appreciable area adjacent each pair 25 of grids, and the function of these flanges is to increase the effective capacity of the circuit constituted by the resonator and to reduce the effective resonator size necessary for a particular resonator frequency. This tube 25 has a central 30 threaded portion 27 for retaining a thrust plate 29 thereon. The main body 33 of the tube 1 carries a flange 35 which has several threaded holes 37, in this case shown, for illustrative purposes only, as three in number. These threaded holes 37 carry thrust screws 39, one end of each 35 of which terminates in a shape suitable for the application of a wrench for turning the screw, or in a slot for receiving a screw driver, while the other end terminates in a socket adapted to receive the ball heads of thrust rods 41, 43. The screws 39 also have lock nuts 45 for maintaining them in their set position. The other end of each 40 of the thrust rods 43 is placed in a socket in the threaded plate 29 similar to the sockets in screws 39. The plate 29 has rigidly fastened to it, as by screws 47, a resilient cantilever leaf member 49. The member 49 is fastened to plate 29 at one 45 end only, in cantilever fashion. The unfastened end of cantilever 49 is adapted to be moved by the movable stem 51 of a micrometer arrangement 53 mounted as by bracket 55 on plate 29. Rotation of handle 57 results in transmission of thrust to cantilever 49 through ball 59, resulting in deflection of the resilient cantilever 49. 50 Thrust rod 41 is socketed at one end in the mem-

ber 49 near the fastened end of this member, and at the other end in its screw 39.

Fig. 2 shows plate 29 with rods 41 and 43 in their normal operating position. These rods are held in position in the actual device by the opposition to deformation of the resonating chamber 7 created largely by atmospheric pressure acting on the evacuated casing 33, as described below. While the cantilever tuning means has been shown as applied only to the first resonating chamber, it is obvious that it could equally well be applied to any of the others.

Resonating chambers 9 and 11 have their rigid walls 15, 17 connected together as by peripheral connection member 61, which carries a flange 63 similar to flange 35. Flange 63 carries screws 65 similar to screws 39, which transmit thrust through thrust rods 67 to plate 29. Resonator 11 has its flexible wall centrally apertured and carries a tube 71 terminating in outer cooling fins 73. Mounted on this tube 71 is another thrust plate 75 carrying thrust screws 77 bearing against thrust rods 79 which in turn bear against flange 63, the usual lock nuts 81 being provided.

Each of the resonating chambers 7, 9, 11 has provided means for supplying or abstracting high frequency energy in the form of concentric line terminal posts 83 whose inner conductors terminate in coupling or pick-up loops 85.

In operation, electrons emitted by the cathode 2 form a beam which may be modulated by supplying suitable modulating potentials or signals to grid 5. The electrons are accelerated by the potential difference between cathode 2, usually maintained at a high negative potential, and rigid wall 13, which acts as an accelerating electrode and is usually grounded. As is well known, the passing of the beam through the first resonating chamber 7, known as the "buncher," effects recurrent changes in velocity of the electrons of the beam. Passage of electrons through the drift tube 25 permits the electrons to bunch, and to give up their energy upon passage through the second resonator 9, known as the "catcher." Output energy can be obtained from the resonator 9. However, in order to prevent the abstraction of energy from affecting the frequency characteristics of resonator 9 and of resonator 7, which may, in some applications of the device, be coupled to resonator 9, the electron beam, now "bunched," is allowed to pass through the further resonator 11, and output energy is obtained from this resonator, which cannot reflect back into the other resonators 7 and 9 to change their frequency characteristics since it is coupled to the other resonators only by the electron beam. The novel tube of this invention thereby includes a buffer stage or resonator as well as the "buncher" and "catcher" stages or resonators. The grids carried by walls 15 and 17 are spaced apart a distance much less than the distance between the grids on opposite ends of tube 25, but are spaced far enough to insure against coupling of the field of resonator 11 back to the field of resonator 9. At the same time, as illustrated in Fig. 1, the grids carried by walls 15 and 17 are sufficiently close together that both resonators 9 and 11 extract energy from the bunched electron beam within a relatively small region where the condition of electron bunching in the electron beam varies but little due to the small transit time.

As is well known, the frequency of operation of such devices as the present depends on the size and shape of the resonating chambers. The

present invention provides means for adjusting the frequency of each of the resonators. Thus, it is clear that turning screws 77 will create a thrust between plate 75 and flange 63, which will be transmitted to the rigid wall 17 and the flexible wall 23 of resonator 11 to create relative thrust therebetween. This thrust is opposed by the action of atmospheric pressure on the evacuated chamber, which tends to collapse the flexible wall. This adjustment of screws 77 therefore causes deformation of the flexible wall 23, thereby changing the resonating frequency of this resonating chamber. Once adjusted, the frequency may be maintained by use of the lock nuts 81 to maintain screws 77 in desired position.

Turning screws 65 will in like manner create relative thrust between the rigid and flexible walls of resonator 9 and cause tuning of this resonator. It will be noted that this tuning cannot affect the tuning of resonator 11, since no thrust is created between the rigid and flexible walls of that resonator by turning screws 65. At most, a slight motion of the whole resonator 11 occurs, due to deformation of flexible wall 21 of resonator 9.

In the same manner, the frequency of resonator 7 can be adjusted by screws 39. Here again, no effect is produced on either of the other resonators. It is obvious that the tuning of each of the resonators is independent of any other, and the resonators may be adjusted in any desired order.

In the case of resonator 7 there is further provided the novel fine cantilever adjustment for tuning above described. It will be seen that turning micrometer handle 57 will create a thrust on resilient cantilever 49 through ball 59. This thrust is transmitted to rod 41 by the cantilever action of member 49 and thence to resonator chamber 7. A dual refinement of tuning is obtained by this means. First, there is the refinement by use of a micrometer screw instead of the ordinary screws 39. There is a second refinement in tuning by use of the cantilever arrangement, even over an ordinary rigid lever arrangement. If an ordinary lever were used, pivoted at screws 47, the motion of rod 41 would be reduced relative to that of micrometer rod 51 by a factor which is proportional to the ratio of their relative distances from the pivot. The novel method here used obtains a further refinement over such a pivoted lever arrangement, since the reduction in deflection of rod 41, using the cantilever arrangement and neglecting the opposing force created by rod 41, is by a factor roughly proportional to the square of the ratio of the relative distances, since the cantilever assumes a roughly parabolic shape. Furthermore, the effect of the opposition of rod 41 to being moved by the application of force to the end of the cantilever 49 is to further reduce the relative motion, and to effect further refinement of tuning. From another point of view, this results in further curvature of the cantilever spring 49, making the displacement of rod 41 proportional to the applied motion by a factor which is inversely proportional to even higher powers of the distance ratio than the second power. It will be seen thus that extremely fine and sensitive tuning adjustments can be made, which is essential for successful operation, especially in small tubes operating at high frequency, where the slightest change in size and shape produces extremely large changes in resonating frequency.

Fig. 3 shows an arrangement in which resona-

tor 2 is coupled back to resonator 1, as by transmission line 112, thereby causing tube 1 to generate oscillations. The output of tube 1 is taken from buffer resonator 11 by means of transmission line 113 to preserve stability of oscillation, and is connected, to any suitable load, such as an antenna.

As many changes could be made in the above constructions and many apparently widely different embodiments of this invention could be made without departing from the scope thereof, it is intended that all matter contained in the above description or shown in the accompanying drawings shall be interpreted as illustrative and not in a limiting sense.

What is claimed is:

1. An electric discharge tube comprising means for generating a stream of electrons, a first apertured hollow resonator axially positioned with respect to the path of said stream and adapted to velocity modulate said electron stream, a second hollow apertured resonator also axially positioned with respect to said path, and adapted to be energized by said stream, a drift tube connecting and spacing said first and second resonators to permit electrons in electron flow therebetween and to permit said velocity modulated stream to become bunched, a third hollow apertured resonator axially placed with respect to said path close to said second resonator, said second and third resonators being coupled to said electron stream sufficiently far apart to prevent coupling of the third resonator field back to the second resonator field, but sufficiently close that said electron stream undergoes little change in bunching while passing between said second and third resonators, and means for abstracting high frequency energy from said third resonator whereby the abstraction of high frequency energy from said electron discharge tube will not affect the resonating characteristics of said second or first resonators.

2. An electron discharge tube comprising an electron gun for generating a stream of electrons, a hollow apertured resonator positioned axially with respect to the path of said stream and having a rigid wall facing said gun and a flexible wall opposite said rigid wall, an intruding portion mounted on said flexible wall and extending toward said rigid wall, and having a flanged portion of extensive area adjacent and parallel to said rigid wall, a second hollow apertured resonator axially positioned with respect to said path and having a flexible wall facing said gun and a rigid wall opposite said last-named flexible wall, a drift tube axially positioned with respect to said path and connecting said flexible walls together, a plate rigidly mounted transversely on said drift tube, a cantilever spring member rigidly fastened at one point to said plate, a micrometer screw adjuster having a fixed portion fastened to said plate and a movable portion to move the free end of said spring perpendicular to said plate, a flange rigidly connected to said first rigid wall, and a thrust rod positioned between said flange and a point on said spring between the fixed point and the end driven by said micrometer screw to transmit thrust from said spring to said flange whereby said first chamber may be tuned by change in its size and shape upon rotation of said micrometer screw.

3. An electron discharge device as in claim 2, in which said flange carries an adjustable screw and in which a second thrust rod is positioned between said adjustable screw and said plate where-

by coarse tuning of said first resonating chamber may be effected by rotation of said screw.

4. An electron discharge tube as in claim 2 further comprising a flanged member connected to the rigid wall of said second resonator, an adjustable screw carried by said flanged member and a second thrust rod placed between said screw and said plate, whereby coarse tuning of said second resonating chamber may be effected by rotation of said screw.

5. A hollow resonator for use in electron discharge tubes comprising a front wall and a rear wall, both walls having aligned apertures adapted to permit the passage of an electron beam therethrough, an inwardly extending portion connected to one of said walls and axially aligned with said apertures, said portion terminating in a flange extending adjacent and substantially parallel to the other of said walls, and having an opening adjacent to the aperture in said other wall, said opening and said last-named aperture containing grids for controlling said electron beam.

6. A hollow resonator for use in electron discharge tubes, comprising a front wall and a rear wall, both walls having aligned apertures adapted to permit the passage of an electron beam therethrough, and an inwardly extending portion connected to one of said walls and axially aligned with said apertures, said portion terminating in a flange extending adjacent and substantially parallel to the other of said walls and having an opening adjacent to the aperture in said other wall.

7. A resonator for use in electron discharge tubes, comprising a casing having a front wall and a rear wall, both of said walls having aligned apertures adapted to permit passage of an electron beam therethrough, an inwardly extending portion connected to one of said walls and axially aligned to said apertures, and cooperating surface means on said portion and the other of said walls for providing increased capacitance between said portion and said other wall, whereby for a given operating frequency the effective size of said resonator may be reduced.

8. A hollow resonator for use in electron discharge tubes, comprising a casing having aligned apertures adapted to permit the passage of an electron beam therethrough, one wall of said casing having a reentrant portion, and cooperating means on said reentrant portion and the opposite wall for providing increased capacitance between said reentrant portion and said opposite wall of said resonator, whereby for a given operating frequency the effective size of said resonator may be reduced.

9. A tunable high frequency device, comprising a hollow resonator having rigid and flexible wall portions, a flexible cantilever member having one end fixed to one of said portions, a thrust member interposed between said cantilever member and the other of said portions, and means operatively coupled to said cantilever member for flexing said cantilever member to thereby relatively displace said wall portions and vary the tuning of said resonator.

10. A tuning control mechanism for a high frequency electron discharge tube having a cavity resonator with a flexible wall portion, said mechanism comprising a tuning control member, a bendable lever adapted to be anchored at one end to said tube and operatively connected to said member, and force transmitting means adapted to be operatively coupled between said lever and

said flexible wall portion, whereby deflection of said flexible wall may be controlled by said control member.

11. High frequency apparatus comprising means for producing a grouped electron stream, a hollow resonator along the path of said stream for extracting energy therefrom, means providing a relatively small space through which said electron stream passes beyond said first resonator, a further hollow resonator along the path of said electron stream beyond said space, said space being sufficiently large to prevent coupling of the field of said further resonator back to the first resonator field, and being sufficiently small to enable said further resonator to couple with the electron stream before it has time to undergo an appreciable change in its condition of bunching beyond said first resonator, and means coupled to said further resonator for extracting energy therefrom.

12. High frequency electron discharge apparatus comprising means for producing an electron stream, three hollow resonators spaced in succession along the path of said stream in energy exchanging relation therewith, means providing an electron bunching space between the first two resonators to permit electron bunching in the stream between said first two resonators, and means providing an electron beam transit space between the second and third resonators which is much shorter than said electron bunching space, so that said second and third resonators are coupled to said electron stream in appreciably closer succession than are said first and second resonators.

13. High frequency apparatus comprising a hollow resonator device having two spaced parts which are relatively movable for varying the frequency of said resonator, and means for effecting relative movement of said parts comprising a resilient lever secured to one of said parts, thrust means interposed between said resilient lever and the other of said parts, and means coupled to said lever for controllably flexing said resilient lever.

14. The apparatus defined in claim 13, wherein said resilient lever is a spring leaf anchored at one end to said one part, and said means for flexing the lever comprises a micrometer assembly mounted on one of said parts.

15. High frequency apparatus comprising a hollow resonator having a first end wall formed with an electron permeable region and an opposed flexible end wall, a hollow tubular member mounted on said flexible wall in alignment with said region, said tubular member extending into said resonator to a point adjacent said region and extending outwardly beyond said flexible wall, and an electron collector electrode on said tubular member externally of said resonator.

16. High frequency apparatus comprising means for producing an electron stream, and three hollow resonators spaced in succession along the path of said stream, said path between the first and second of said resonators being several times as long as the path between the second and third of said resonators.

17. Apparatus as in claim 16, further including

means coupling said first and second resonators together, and means coupled to said third resonator for extracting high frequency energy therefrom, whereby variations in said energy extraction do not affect the operation of said coupled first and second resonators.

18. Apparatus as in claim 16, further including a pair of independent outputs and means coupling one of said outputs to said second resonator and means coupling the other of said outputs to said third resonator.

19. High frequency apparatus comprising a hollow resonator having a pair of end walls, one of said end walls being formed with an electron-permeable region, a hollow tubular member mounted on the other of said walls in alignment with said region, said tubular member extending into said resonator to a point adjacent to said region and extending outwardly beyond said other wall, and an electron collector electrode conductively connected to and closing said tubular member externally of said resonator.

20. High frequency apparatus comprising a hollow resonator having a pair of opposed walls, one of said walls being formed with an electron-permeable region, a hollow tubular member mounted on the other of said walls in alignment with said region, said tubular member extending outwardly of said resonator away from said other wall, and an electron collector electrode conductively connected to and closing said tubular member outside said resonator.
